US00D937907S

(12) **United States Design Patent** (10) **Patent No.:** **US D937,907 S**
Hattori et al. (45) **Date of Patent:** **** Dec. 7, 2021**

(54) **INSULATING MATERIAL FOR ELECTRIC COMPRESSOR**

(71) Applicant: **MITSUBISHI HEAVY INDUSTRIES THERMAL SYSTEMS, LTD.**, Tokyo (JP)

(72) Inventors: **Makoto Hattori**, Tokyo (JP); **Hiroyuki Kamitani**, Tokyo (JP); **Hiroto Higuchi**, Tokyo (JP); **Takayuki Takashige**, Tokyo (JP)

(73) Assignee: **MITSUBISHI HEAVY INDUSTRIES THERMAL SYSTEMS, LTD.**, Tokyo (JP)

(**) Term: **15 Years**

(21) Appl. No.: **29/708,739**

(22) Filed: **Oct. 9, 2019**

(30) **Foreign Application Priority Data**

Apr. 12, 2019 (JP) 2019-008050

(57) **CLAIM**

The ornamental design for an insulating material for electric compressor, as shown and described.

DESCRIPTION

FIG. 1 is a perspective view of an insulating material for electric compressor.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

1 Claim, 7 Drawing Sheets
